AIR CONDITIONER

William A. Norris, Alhambra, Calif., assignor to
 William H. Fabry and Rae H. Fabry, as joint
 tenants, with right of survivorship

Application January 31, 1941, Serial No. 376,787

3 Claims. (Cl. 261—91)

This invention relates to air conditioners.

The general object of the invention is to provide an improved evaporative cooler which is particularly adapted for use as a portable unit for the home or office.

A more specific object of the invention is to provide an evaporative cooler including a receptacle and container arranged above the receptacle with novel means for transferring water from the receptacle to the container.

Another object of the invention is to provide a novel evaporative cooler including a novel water distributing means for humidifying a column of air.

A further object of the invention is to provide an evaporative cooler including a novel pump member.

Other objects and advantages of the invention will be apparent from the following description taken in connection with the accompanying drawing, wherein:

Fig. 1 is a central sectional view through an evaporative cooler embodying the features of my invention;

Fig. 2 is a top plan view of the cooler with parts broken away;

Fig. 3 is a side elevation on a reduced scale; and

Fig. 4 is a fragmentary, central sectional, view showing the pump member.

Referring to the drawing by reference characters, I have shown my invention as embodied in an evaporative cooler which is indicated generally at 10. As shown, the cooler includes a cylindrical housing 11 having a bottom 12 therein to thereby form a receptacle 12'. The bottom 12 has its periphery seated in a bead 13 in the housing and may be suitably welded as at 14 or otherwise secured in place.

The top of the housing 11 includes an outwardly directed bead 15 which is engaged by a down turned flange 16 on an annular ring 17. The ring 17 has the edge of a dome shaped articulated mesh member 18 secured thereto as by soldering and the flange 16 is removable to allow access to the interior of the housing.

The housing intermediate its length includes slots 19 which extend more than half way around the housing to provide outlets for the conditioned air. Extending across the slots 19 I show a grill which includes vertical members 20 and arcuate members 21 which are secured as by welding to the vertical members. At the end vertical members 20' are secured to the housing

as by screws 22 so that the grill may be removed for cleaning or other purposes.

Spaced above the bottom 12 I show a transverse partition 23 which has a downwardly extending peripheral flange 24 thereon and which is provided with a central aperture 25. The flange 24 fits within and is secured to a collar 26. The latter being secured to the housing 11. The collar 26 includes an upwardly directed frustoconical portion 27 which has a downturned lip 28 on the upper end thereof.

The partition 23 forms a distributing surface for water pumped from the receptacle 12' by pump means to be later described. The collar 26 portion 27 and lip 28 form a splash guard.

The housing includes a transversely extending bracket 29 which has flanged ends 30 secured to the housing and has inwardly directed portions 31 which surround a motor 32 and are clamped 20 against the motor by fastening means 33.

The motor 32 includes an armature shaft 34 which projects upwardly at 35 and downwardly at 36. On the armature shaft portion 35 I secure as by a set screw a fan member 38 which 25 includes a pair of superimposed fan members 39 and 40. The details of the fan form no part of the present invention but are shown and described in my copending application, Serial No. 375,226, filed Jan. 21, 1941.

30 The lower end portion 36 of the armature shaft extends towards the partition 23 and is coaxial with the aperture 25 in the partition and receives a boss portion 41 of a pump member indicated generally at 42.

35 The pump member 42 includes a lower portion 43 which is in form of a hollow truncated cone and a head portion 44 coaxial with the portion 43. The head portion 44 includes a depending flange 45 which receives the upper end of the 40 cone 43 to which it is shown as welded at 46. The boss portion 41 previously mentioned is on the head portion 44 and has a set screw 46 by means of which it is held on the armature shaft 36.

45 The cone of the pump member 42 terminates a short distance from the bottom 12 of the housing 11. The head portion 44 includes a recess 47 forming a wall 48 through which spaced apertures 49 extend. The splash guard collar 27 is arranged in alignment with the apertures 49 and the lip 28 is above the apertures 49.

To control the circuit to the motor 32 I provide a switch 50 of standard type which may be secured to the housing 11 as shown in Figs. 2 and 3.

When the device 10 is used as a fan to merely circulate the air in a room, the switch 50 is operated and the motor 31 drives the fan member 38 which draws air through the mesh member 18 and discharges it through the slots 19.

When the device is used as an evaporative cooler, the space within the housing 11 above the bottom 12 is filled with water, as shown in Fig. 1. In order to introduce the water, I provide a wedge shaped filling spout 51 as shown in Figs. 2 and 3. The spout 51 communicates with the interior of the housing 11 through an aperture 52 therein. As a closure for the spout 51 I provide a removable cover 53.

It will be seen that water enters the interior of the cone 43 through the bottom thereof and upon rotation of the cone the water will be raised therein by centrifugal action. The water is discharged at the top of the cone through the aperture 48 and is thrown against the splash guard 27 and distributed onto the partition 22. The water forms a layer on the partition 23. Any excess water is returned to the main body by passing through the aperture 25.

As the air is directed downwardly by the fan upon the surface of the water on the partition, water is evaporated and the air is thereby cooled. The air striking the surface of the water will produce some circulation and agitation therein.

To prevent marring of surfaces on which the device 10 may be placed and to reduce vibration, I may provide a plurality of rubber cushion members 54 which are engaged by socket members 55 secured to the bottom 12.

From the foregoing description it will be apparent that I have invented a novel evaporative cooler that is economical to manufacture, attractive in appearance, and highly efficient for its intended purpose.

Having thus described my invention, I claim:

1. In an evaporative cooler, a housing having a closed bottom and a reticulated mesh top and having an intermediate partition with an aperture therein, said partition having a peripheral flange, a motor mounted within said housing and having a shaft, water lifting means mounted below said motor on said shaft, a shield member being disposed above said partition and comprising a portion having a flange enjoining said par-

tition flange, means to secure said flanges to the housing, said water lifting means being adapted to raise water from said bottom to a location above said partition, said housing having an air outlet above said partition, and a fan disposed above said motor on said shaft and adapted to direct a column of air upon water on said partition.

2. In an evaporative cooler, a housing having a closed bottom and a reticulated mesh top and having an intermediate apertured partition therein, a motor mounted within said housing and having a shaft, a head member mounted below said motor on said shaft, a truncated cone mounted on said head, the large end of said cone extending upward, the lower end of said cone being apertured, a shield member disposed about the upper end of said cone and comprising a portion secured to said housing, said portion including a down-turned lip, said head portion having spaced holes therethrough, said cone being adapted to raise water from said bottom to a location above said partition, said housing having an air outlet above said partition, and a fan disposed above said motor on said shaft and adapted to direct a column of air upon water on said partition.

3. In an evaporative cooler, a housing having a closed bottom and a reticulated mesh top and having an intermediate partition with an aperture therein, a motor mounted within said housing and having a shaft, a truncated cone in said housing, the larger end of said cone being upward, the lower end of said cone being apertured, a shield member disposed about the upper end of said cone and comprising a cylindrical portion secured to said housing, said cylindrical portion having an upwardly tapering frustro conical portion thereon, said frustro conical portion including a down-turned lip, said cone having a hollow upper head portion with spaced peripheral holes therethrough, said cone being adapted to raise water from said bottom to a location above said partition, said housing having an air outlet above said partition, and a fan disposed above said motor on said shaft and adapted to direct a column of air upon water on said partition.

WILLIAM A. NORRIS.
